JAMES A. KINNEY, OF LEBANON, PENNSYLVANIA, ASSIGNOR TO BETHLEHEM STEEL COMPANY.

RAIL-JOINT-PLATE PRESS.

Application filed July 30, 1926. Serial No. 125,846.

My invention relates to a press for punching and shaping metal plates, bars etc; and particularly presses used in the manufacture of rail joint plates of the type which are provided with flanges shaped to fit the base flanges of rails.

Heretofore presses have been used for finishing plates, that is, equipped for the purpose of punching the holes in the web por-

10 portion of the plate to receive the rail fastenings, notching the flanges of the plate to receive the spikes, and straightening in order to secure a true and uniform plate. Certain rail joint plates of the type for use with joints 15 commonly known as "continuous rail joints" are made with a V-shaped transversely disposed flange portion the base of which is adapted to extend beneath the rail. It is customary with the latter type of plates to 20 roll a bar of considerable length having the base of the flange portion bent out of the plane of the base, to facilitate the rolling operation, and after shearing the plates to the desired length the base is bent to its true position 25 in a press suitable for the purpose. It has been the general practice to provide a separate press for each of the aforementioned finishing operations and such presses were usually arranged side by side so that the operators 30 carry the plate or slide it on skids from one press to the other, as each operation was completed. This necessitated the construction of a number of extremely large and heavy presses to afford the necessary rigidity 35 and strength required to perform the separate operations of punching, notching and straightening. The plates used in present day railway practice are extremely heavy 40 and it is quite an onerous task to handle the plates manually in order to transfer them from press to press. It is therefore the object 45 of my invention to provide a machine which is a self-contained unit capable of performing all the operations usually required to finish a rail joint plate.

More specifically the object is to provide a machine for punching, notching and straightening rail joint plates and includes a mechanism for mechanically handling the plate 50 step by step during its passage through the machine.

A still further object of my invention is the

provision of a machine for finishing rail joint plates comprising tools for punching the plate, tools for simultaneously straightening and notching the plate and a mechanism synchronized with the operation of the work tools to intermittently advance the plate step by step to its different positions before the tools and eject the finished plate from the machine.

In its general aspect, my invention comprises the combination with a bed plate carrying a series of dies, of a reciprocating head carrying punches which cooperate with certain of said dies to aperture the web of the plate, a second reciprocating head carrying a former adapted to cooperate with an anvil carried by the bed plate for straightening the web portion of the plate and for the further purpose of securely holding the plate during the subsequent operation, a third reciprocating head the line of action of which is at right angles to the line of action of the aforementioned heads and carrying tools which cooperate with dies carried by the bed plate for notching the extending edge of the flange portion of the plate, said third head also functioning to bend the base of flange of the continuous rail joint type of plate into correct position when plates of that type are being operated upon, a carrier mechanism carried by one of the first mentioned heads for mechanically advancing the plate step by step into the line of action of the aforementioned tools and ejecting the finished plate from the machine, and power means for operating the several heads and carrier mechanism in a predetermined timed relation.

The novel features will be more fully understood from the following description and claims taken with the accompanying drawings in which:

Fig. 1 is a front elevation of a machine embodying one form of my invention;

Fig. 2 is a cross sectional view taken on line II—II Fig. 1;

Fig. 3 is a cross sectional view taken on line III—III Fig. 4;

Fig. 4 is a partial view of the rear of the machine shown in Fig. 1 and constitutes a conventional section taken on line IV—IV Fig. 3.

Fig. 5 is a similar section to Fig. 3 some-

what enlarged and illustrates the rail joint plate of the continuous type in various stages of finishing;

Fig. 6 is a cross sectional view taken on line 5 VI—VI Fig. 1;

Fig. 7 is a cross sectional view of the stripping device attached to the straightening or clamping head; and,

Fig. 8 is a detail of the cams for actuating 10 the vertical heads.

Referring to the drawings: 10 indicates a bed plate and 11 a vertical housing comprising column members 12 tied at their upper ends by the cross tie 13.

15 A crank shaft 14 is rotatably mounted on suitable bearings attached to the column members 12. Journaled on the crank pin of said shaft 14 are a pair of spaced pitman members 15 which are pivoted to the cross 20 head 16, as at 17. The rotation of the crank shaft 14 causes the reciprocation of the cross head 16 which is constrained to move in straight lines by suitable guideways 18 formed in the opposed faces of the column 25 members 12. Mounted at the end of the cross head 16 (see Fig. 5), are multiple punches 19 which cooperate with dies 20 carried by the bed 10 to aperture the web of the rail joint plate when the cross head 16 is reciprocated 30 as hereinafter described.

35 A toggle shaft 21 is rotatably mounted in suitable bearings attached to the column members 12 and has formed thereon, at each end thereof, within the housing, a pair of laterally extending lugs 22 which project in a downward direction and has also formed thereon, at about the same positions as the lugs 22 along the length of the shaft, a pair 40 of lugs 23 which extend upwardly. Each pair of lugs 22 are apertured to receive a pin upon which is journaled a link member 24. Each of the link members 24 is pivoted to the crosshead 25 in spaced relation to each other, and said crosshead is mounted to reciprocate in suitable bearings 26 formed in the housing 12. Each pair of lugs 23 is apertured to receive a pin which carries a roller 27.

50 A cam disc 28 is keyed to each journal portion of the crank shaft 14, (see Figs. 1, 6 and 8) and is positioned on said shaft so that the roller 27 engages its cam surface whereby the rotation of the crank shaft causes the rocking of the toggle shaft 21 in one direction. In 55 order to rock the toggle shaft in the opposite direction, I provide second cam disc 29 keyed to each journal portion of the crank shaft 14 and in juxtaposition with the disc 28. The periphery of the disc 29 engages a roller 30 mounted on the arm 31 which is pivoted at one end to the cross tie 13, as at 32, and extends across the crank shaft 14. An adjustable link 33 is pivoted to the extending end of the arm 31 and hinged at its other end to 60 the lugs 34 extending laterally from the lugs

23, as at 35, Fig. 6. The discs 28 and 29 are so related to each other and the cam surfaces thereof so shaped that, when the crank shaft 14 rotates the toggle shaft is caused to rock intermittently back and forward where- 70 by the crosshead 25 is reciprocated in a pre-determined time relation with respect to the reciprocation of the cross head 16.

Detachably secured to the lower face of the crosshead 25 is a former 36 which is 75

shaped as a counterpart of the inside shape of the rail joint plate. When said crosshead is in its lowermost position the former 36 coacts with an anvil 37, carried by the bed plate 10, and which is shaped as counterpart 80 of the outside shape of said plate, to straighten the plate longitudinally and laterally and at the same time hold it firmly during the subsequent operation of bending and notching the flange portion of the plate as hereinafter described. A crank shaft 38 is journaled in suitable bearings mounted on the bed plate 10. A pair of spaced pitmen 39 is journaled on the crank portion of shaft 38 and is pivotally connected to a horizontally disposed crosshead 40 which is slidably mounted in suitable guideways 41 on the bed plate 10. A multiple punch 42 is detachably secured to the front of the crosshead 40 and cooperates with dies 43 carried 90 on the bed plate 10 to notch the flange portions of the rail joint plate when the crosshead 40 is reciprocated. The reciprocation of the crosshead 40 is so timed with respect to the reciprocation of the crosshead 25, that, 100 while the plate is firmly gripped between the former 36 and the anvil 37, the crosshead 40 advances to notch the flange of the plate and when the plate is of the continuous rail joint type aforesaid, bends the flange which 105 is adapted to extend beneath the rail base, into its correct position against the side of the former 36.

110 The rail joint plate is moved step by step successively to its respective position before the finishing tools by a mechanism described as follows. A pair of cam discs 44 and 45 respectively is keyed to the central shaft portion of the crank shaft 38 which is coaxial with the journal portion of said shaft. The 115 cam discs 44 and 45 are coaxial and are disposed at 90° angular relation with respect to each other and engage with rollers 46 and 47, respectively, rotatably mounted on the spaced arms 48 and 49, respectively, which 120 extend laterally from the rock shaft 50.

125 It will be seen that arms 48 and 49 are disposed at right angles to each other and the arm 48 projects vertically so that the roller 46 engages the periphery of the disc 44 at a point which is in close proximity to the horizontal plane passing through the axis of rotation of the crank shaft 38, whereas the arm 49 projects horizontally and the roller 47 engages the periphery of the disc 45 at a 130

point which is in close proximity to the vertical plane passing through the axis of rotation of said crank shaft whereby rotation of the latter causes the rock shaft 50 to rock about its axis a predetermined extent. The crosshead 25 is provided with openings to receive a pair of tubular bearing members 51. The members 51 extend laterally beyond the forward face of the crosshead 25 and project through suitable elongated clearance slots 52 provided in the crosshead 16 so that the movement of the latter is independent of the movement of the crosshead 25. Each member 51 has slidably and rotatably mounted therein a slide rod 53 which extends beyond the ends of said members. The slide rods 53 are connected respectively to arms 54, which extend upwardly from the rock shaft 50 by means of a reach rod 55' which is hinged to the slide rod 53 and swiveled to the arms 54, whereby the rotation of the crank shaft 38 causes the reciprocation of the slide rods 53 without interfering with the free rotary movement of same.

25 Suspended from each of the slide rods 53 is a carrier member 55 positioned one at each side of the die block 56. Each carrier member 55 is provided with a pair of spaced finger plates 57 which are detachably fastened to the inside face thereof; the finger plates 57 of one of the carrier members being disposed opposite the finger plates 57 of the other carrier member. The finger plates are shaped to conform with the exterior shape of rail joint plate being handled and opposed pairs of finger plates are adapted to support the rail joint plate when the carrier members 55 are in their closed position as hereinafter described. Splined to each of the slide rods 40 53 is a sleeve 58 which is rotatably secured to the crosshead 25 by suitable means, such as the adjustable brackets 59.

Extending laterally from each sleeve 58 are a pair of arms 60 and 61, which is disposed in the same plane and at an obtuse angle with respect to each other, and the bifurcated outer ends of said arms are provided with rollers 62. A pair of cam plates 63 is fixed to a stationary part of the machine, such as the columns 12, and is spaced apart with their respective cam surfaces directly toward each other. Referring to Fig. 4, during the reciprocation of crosshead 25, the rollers 62 are adapted to engage the cam plates 63, so that when said crosshead moves to its lower position the arms 60 are moved toward each other, thereby rotating the left hand sliding rod 53 in a clockwise direction and right hand sliding rod 58 in a counter-clockwise direction and thereby swinging the carrier members 55 to their open position. When crosshead 25 moves upwardly, from its position shown in Fig. 4, the arms 61 engage their respective cam plates and are moved toward each other thereby rotating

the respective sliding rods 53 in the reverse direction to that aforementioned and thereby swinging the carrier members 55 to their closed position.

The crank shafts 14 and 38 are rotated through suitable gearing by the motor 64. The gearing comprises a gear keyed to the armature shaft of the motor 64 meshing with a gear 65 keyed to the shaft 66 which is journaled in suitable bearings mounted on the bed plate 10. Also keyed to the shaft 66 is a gear 67 which meshes with a gear 68 loosely mounted on the shaft 69 which is journaled in bearing formed in the columns 12. A suitable clutch mechanism indicated generally by the figure 70, operated by the treadle 71 is provided to connect or disconnect the gear 68 to or from the shaft 69 so that as long as the treadle is depressed the motor will drive the shaft 69, and when the treadle is released the shaft 69 is brought to rest in a predetermined position without stopping the motor. The clutch mechanism may be of any well known type and construction and is not, therefore, shown and described in detail.

Keyed to the shaft 69 is a gear 72 in mesh with the gear 73 which is fixed to the extending end of the crank shaft 14. The shaft 69 extends through the housing 11 and has a gear 74 keyed at its end which meshes with a gear 75 keyed to the end of the crank shaft 38. It will be seen that when the motor is running and the treadle is depressed, the crank shafts 14 and 38 will rotate in unison.

In operation assuming the machine to be in its starting position shown in Fig. 1 it will be noted that the crosshead 25 is in its lowermost position, crosshead 40 is in its advanced position, the carrier members 55 are at about the midway position in their horizontal direction of travel and the crosshead 16 is almost at its lowermost position. The clutch is operated by pressing down the treadle 71 and the shaft 69 is caused to rotate.

The gear 73 rotates in the direction of the arrow shown at Fig. 6 and the crosshead 16 moves to its lowermost position and then begins to lift. As the crosshead 16 begins to lift the periphery of the cam disc 28 recedes from the roller 27 and the cam disc 29 lifts the arm 31, thus rocking the toggle shaft 21 in the direction to cause the crosshead 25 to raise. As the latter lifts the carrier members 55 being supported thereon also rise therewith and are forced into their closed position by the cam plates 62. A rail joint plate A is placed on the forwardly oppositely disposed pair of finger plates 57. In the meanwhile the crosshead 40 begins to recede and when the crossheads 16 and 25 approach their uppermost respective positions the periphery of cam disc 45 recedes from the roller 47 and allows the cam disc 46 to rock the rock shaft 50 whereby the slide rod 53 is moved longitudinally while it is being raised.

upwardly on the crosshead 25, so that, when the vertically disposed crossheads reach their uppermost respective positions the rail joint plate is superposed with respect to the dies 20.

5 The crank shaft 14 passes over its top center, the crosshead 16 moves downwardly, the cam disc 29 recedes from the roller 30 and cam surface of the disc 28 engages the roller 27 so that the toggle shaft 21 is rocked and 10 wedges the crosshead 25 downwardly. The downward movement of the latter causes the carrier members 55 to drop and the rail joint plate is lowered in its correct position on the block supporting the dies 20 in the line of 15 action of the punches. The crosshead 16 continues its downward movement, though somewhat slower than the downward movement of the crosshead 25, and the punches 19 aperture the web of the rail joint plate for the reception of the rail fastening bolts. During 20 the aforesaid punching operation of the crosshead 16, the crank shaft 38 rotates to cause the crosshead 40 to advance toward the die block and the cam discs 44 and 45 are so positioned that the periphery of the disc 44 recedes from the roller 46, whereas, the cam disc 45 engages the roller 47 and causes the rock shaft 50 to rock in a counter clockwise direction, see Fig. 6, thus, moving the slide 25 rods 53 longitudinally carrying the carrier member therewith. It will be seen that the 30 cycle of operations comprises the following steps; first the downward movement of the crosshead 25 carrying the carrier members 55 downwardly, then the downward movement of the crosshead 16, performing its punching operation and the advancement of the crosshead 40 while the carrier members 55 are being moved forwardly longitudinally.

35 In the forward position of the carrier member the rearwardly positioned pair of finger plates 57 are disposed in their correct position beneath the rail joint plate resting on the dies 20 and a new rail joint plate is placed upon the forwardly disposed pair of finger plates 57. When the vertically reciprocable crossheads 16 and 25 again are caused to rise, as previously described, and the carrier members move to their rearmost position, the rail joint plate previously punched is superposed over the anvil 37 and the new rail joint plate is superposed correctly over the dies 20. During 45 the continued operation of the machine the crosshead 16 punches the web of the new plate, the crosshead 25 operates to straighten the previously punched plate and firmly holds same while the crosshead 40 advances. The advancing crosshead 40 bends the inwardly projecting flange of the rail joint plate to its 50 correct position and at the same time notches the edge of the flange for the reception of the spikes. When the crosshead 25 is again raised and the crosshead 40 is retracted the finished plate falls from the machine. If the 55 finished rail joint plate sticks to the former

36 attached to the crosshead 25, the spring pressed plungers 76 (see Fig. 7), eject the plate from the machine. Strippers 77, attached to the crosshead 25, (see Fig. 6) are provided to strip the rail joint plate off the 70 punches which are attached to the crosshead 16. During the initial upward movement of the crosshead 16, the crosshead 25 remains stationary and in this manner the strippers are effective to remove the plate off the 75 punches, but, are moved from path of the next plate to be punched when the crosshead 25 is raised.

It will be seen from the foregoing description that I have devised a novel machine of 80 unitary construction for finishing rail joint plates and provide a mechanism which feeds the work to the tools in sequence to the working steps.

While I have shown my invention in but 85 one form, it will be obvious to those skilled in the art that it is not so limited, but is susceptible of various other changes and modifications without departing from the spirit thereof, and I desire, therefore, that only such 90 limitations shall be placed thereupon as are imposed by the prior art or as are specifically set forth in the appended claims.

Having thus described my invention what 95 I claim as new and desire to secure by Letters Patent is:

1. In a machine for finishing rail joint plates, the combination of a plurality of reciprocating heads, tools mounted on said heads, a carrier member slidably mounted on one of said heads for feeding the work to the said tools, means to operate said heads, and means to reciprocate said carrier member in a direction angularly to the direction of the operation of the head to which it is 105 mounted.

2. In a machine for finishing rail joint plates, the combination of a plurality of reciprocating heads, tools mounted on said heads, a carrier member for feeding the work to said tools, means to reciprocate said heads in timed relation with respect to one another, and means operating in timed relation with the operation of said heads to lift said carrier member and move it angularly with respect to 110 the line of movement of the heads.

3. In a machine for finishing rail joint plates, the combination of a series of finishing tools, a carrier member for feeding the work to said tools, means to operate said tools, and means operating in sequence with the operation of said tools to lift said carrier member and move it angularly with respect to the line 115 of action of said tools.

4. In a machine for finishing rail joint plates, the combination of a series of finishing tools, a carrier member for feeding the work to the line of action of said tools, means to operate said tools, means to operate said tools in timed relation with respect to each other, 120

- and means operating in sequence with the operation of said tools to lift said carrier member and move it angularly with respect to the line of action of said tools.
5. In a machine, the combination of a bed plate, a head carrying punching tools, dies carried by said bed plate for cooperating with said punching tools to aperture the work, an anvil, a head for cooperating with said anvil to hold the work, a head carrying notching tools, dies carried by said bed plate for cooperating with said notching tools, a carrier member for feeding the work to the line of action of said tools, means to reciprocate said heads, and means to actuate said carrier member in sequence with the operation of said heads.
6. In a machine, the combination of a head carrying a punching tool, a die for cooperating with said punching tool, an anvil, a head carrying a former for cooperating with said anvil to hold the work, a head carrying a notching tool, a die for cooperating with said notching tool, a carrier member slidably mounted in one of said heads, means to reciprocate said heads, and means to reciprocate said carrier member transversely with respect to the line of action of the head upon which it is mounted.
7. In a machine, the combination of a head carrying a punching tool, a die for cooperating with said punching tool, an anvil, a head carrying a former for cooperating with said anvil to hold the work, a head carrying a notching tool, a die for cooperating with said notching tool, a carrier member slidably mounted in one of said heads, means to reciprocate said heads, means to reciprocate said carrier member transversely with respect to the line of action of the head upon which it is mounted, a stationary member, and means for cooperating with said stationary member for rocking said carrier member.
8. In a machine, the combination of a head carrying a punching tool, a die for cooperating with said punching tool, an anvil, a head carrying a former for cooperating with said anvil to hold the work, a head carrying a notching tool, a die for cooperating with said notching tool, a pair of rods slidably mounted in one of said heads, a carrier member depended from each of said rods, means to reciprocate said heads, and means to reciprocate said rods.
9. In a machine, the combination of a stationary bed plate, a housing, a head carrying a punching tool, a die for cooperating with said punching tool, an anvil, a head carrying a former for cooperating with said anvil to straighten and hold the work, a head carrying a notching tool adapted to operate in a path at substantially right angles to the path of the first mentioned heads, a die for cooperating with said notching tool, a crank shaft rotatably mounted on said housing, a pitman connecting said crank shaft with said head carrying the punching tool, a toggle shaft, a plurality of lug members projecting laterally from said toggle shaft angularly disposed with respect to one another, a roller mounted on one of said lug members, an arm member pivoted to a stationary part of the machine, a roller mounted on said arm, a link member connecting said arm to one of said lug members, a link member connecting said head carrying a former to one of said lug members, cam means mounted on said crank shaft engaging said rollers whereby the rotation of said crank shaft causes the head carrying a former to reciprocate, a pair of tubular members car-
- pitman connecting said crank shaft with said head carrying the punching tool, a toggle shaft, a plurality of lug members projecting laterally from said toggle shaft angularly disposed with respect to one another, a roller mounted on one of said lug members, an arm member pivoted to a stationary part of the machine, a roller mounted on said arm, a link member connecting said arm to one of said lug members, a link member connecting said head carrying a former to one of said lug members, cam means mounted on said crank shaft engaging said rollers whereby the rotation of said crank shaft causes the head carrying a former to reciprocate, a pair of tubular members carried by the last mentioned head, a rod slidably mounted in each of said tubular members, a carrier member depended from each of said rods, a crank shaft journaled on said bed plate, a pitman connecting the last mentioned crank shaft with the head carrying a notching tool, a rock shaft journaled on said bed plate, arms projecting from said rock shaft, rollers mounted respectively on said arms, cam means mounted on the last mentioned crank shaft engaging said rollers whereby rotation of said crank shaft causes the rock shaft to rock, other arms projecting from said rock shaft, a swivel connection between the last mentioned arms and the aforementioned rods respectively, a sleeve member splined to each of said rods, arms carrying rollers projecting laterally from said sleeves, cam plates fixed to the housing adapted to engage the last mentioned rollers whereby reciprocation of the head carrying said rods causes the latter to turn about their longitudinal axes, and means to rotate said crank shafts in unison.
10. In a machine, the combination of a bed plate, a housing, a head carrying a punching tool, a die for cooperating with said punching tool, an anvil, a head carrying a former for cooperating with said anvil to hold the work, a head carrying a notching tool adapted to operate in a path at substantially right angles to the path of the first mentioned heads, a die for cooperating with said notching tool, a crank shaft rotatably mounted on said housing, a pitman connecting said crank shaft with said head carrying the punching tool, a toggle shaft, a plurality of lug members projecting laterally from said toggle shaft angularly disposed with respect to one another, a roller mounted on one of said lug members, an arm member pivoted to a stationary part of the machine, a roller mounted on said arm, a link member connecting said arm to one of said lug members, a link member connecting said head carrying a former to one of said lug members, cam means mounted on said crank shaft engaging said rollers whereby the rotation of said crank shaft causes the head carrying a former to reciprocate, a pair of tubular members car-

ried by the last mentioned head, a rod slidably mounted in each of said tubular members, a carrier member depended from each of said rods, a crank shaft journaled on said bed plate, a pitman connecting the last mentioned crank shaft with the head carrying a notching tool, a rock shaft journaled on said bed plate, arms projecting from said rock shaft, rollers mounted respectively on said arms, cam means mounted on the last mentioned crank shaft engaging said rollers whereby rotation of said crank shaft causes the rock shaft to rock, other arms projecting from said rock shaft, a swivel connection between the last mentioned arms and the aforementioned rods, arms carrying rollers projecting from said rods, and means to rotate said crank shafts in unison.

11. In a machine, the combination of a bed plate, a head carrying a punching tool, dies for cooperating with said punching tool, an anvil, a head carrying a former for cooperating with said anvil to hold the work, a head carrying a notching tool adapted to operate in a path substantially at right angles to the path of the first mentioned heads, a carrier means slidably mounted on one of said heads, means to reciprocate the heads in a predetermined cycle whereby the head carrying the carrier means remains stationary during a period of the movement of the other heads, and means actuated in timed relation to the movement of the latter heads for reciprocating said carrier means.

12. In a machine for finishing a rail joint plate, the combination with a series of finishing tools, of a carrier means for feeding the work to said tools, means to operate said tools in a predetermined cycle, and means operating in sequence with the operation of said tools to lift said carrier means and move it angularly with respect to the line of action of said tools.

13. In a machine for finishing a rail joint plate, the combination of a punching tool, a notching tool, means to actuate said tools, and means to feed the work to the line of action of said tools in sequence to the operation of the latter, said feeding means comprising a reciprocatory member having a pair of rods slidably and rotatably mounted thereon, a carrier member mounted on said rods, means to reciprocate the first mentioned member, means to cause axial movement to said rods, and means to rotate said rods.

14. In a machine for finishing a rail joint plate, the combination with vertical reciprocating heads, of a horizontal reciprocating head, means for reciprocating said heads, and a mechanism actuated by said means for advancing the work step by step to a position before said heads, said mechanism comprising a reciprocatory member having a pair of rods slidably and rotatably mounted thereon, a carrier member mounted on said rods,

means to reciprocate said first mentioned member, means to cause axial movement to said rods, and means to rotate said rods.

15. In a machine for finishing a rail joint plate, the combination of a bed plate, a housing, a punching tool mounted in said housing, a notching tool mounted on said bed plate, a straightening tool mounted in said housing, means to operate said tools, and a mechanism actuated by said means for advancing the work step by step to the line of action of said tools, said mechanism comprising a reciprocatory member having a pair of rods slidably and rotatably mounted thereon, a carrier member mounted on said rods, means to reciprocate said first mentioned member, means to cause axial movement to said rods, and means to rotate said rods.

16. In a machine, the combination of a punching tool, a straightening tool, a notching tool, means to reciprocate said straightening tool, means to reciprocate said punching tool and said notching tool relatively to the straightening tool, a carrier member for moving the work to said tools, means to move said carrier member with said straightening tool, and means to move said member relatively to said straightening tool.

17. In a machine, the combination of relative reciprocatory heads, tools carried by said heads, means to actuate said heads, a carrier device slidably mounted on one of said heads, and means to reciprocate said carrier device independent of the movement of said head.

18. In a machine, the combination of relative reciprocatory heads, punching tools carried by one of said heads, a straightening tool carried by the other head, a crank shaft adapted to continuously operate the punching tools, means actuated by the crank shaft for intermittently operating the straightening tool, a carrier means slidably mounted on the head carrying the straightening tool, and means to reciprocate said carrier member.

19. In a machine, the combination of relative reciprocatory heads, punching tools carried by one of said heads, a straightening tool carried by the other head, a crank shaft adapted to continuously operate the punching tools, means actuated by the crank shaft for intermittently operating the straightening tool, a carrier means slidably mounted on the head carrying the straightening tool, means to reciprocate said carrier member, and finger members mounted on said carrier means for engaging the edges of the work.

20. In a machine, the combination of relative reciprocatory heads, punching tools carried by one of said heads, a straightening tool carried by the other head, a crank shaft adapted to continuously operate the punching tools, means actuated by the crank shaft for intermittently operating the straightening tool, a carrier means slidably mounted on the head carrying the straightening tool, means

to reciprocate said carrier member, and detachable finger members mounted on said carrier means for engaging the edges of the work.

- 5 21. In a machine, the combination of a bed plate, a head carrying punching tools, an anvil, a head for cooperating with said anvil to hold the work, a head for bending the work, a carrier member for feeding the work to the 10 line of action of said tools, means to reciprocate said heads, and means to actuate said carrier member in timed relation with the operation of said heads.
22. In a machine, the combination of relative reciprocating heads, punching tools carried by one of said heads, a straightening tool carried by the other head, means to continuously operate the head carrying the punching tools, means for intermittently operating 15 the head carrying the straightening tool, carrier means for feeding the work to the line of action of the tools, and means to operate 20

said carrier means in sequence with the operation of said tools.

23. In a machine, the combination of a tool, 25 a carrier member for engaging the work and feeding it to said tool, means to operate said tool, means to move said carrier member transversely to the line of action of said tool, and means to move said carrier member transversely with respect to its first mentioned movement to disengage the work. 30

24. In a machine, the combination of a tool, 35 a carrier member for engaging the work and feeding it to said tool, means to operate said tool, means to elevate said carrier, means to move said carrier transversely to the line of action of said tool, and means to move said carrier transversely with respect to its first movement to disengage the work. 40

In testimony whereof I hereunto affix my signature.

JAMES A. KINNEY.
